METHOD OF CONTROLLING THE TENSION
OF STRANDS

Sherman L. Gerhard, La Grange, Ga., assignor to
United States Rubber Company, New York,
N. Y., a corporation of New Jersey

Application December 2, 1943, Serial No. 512,571

4 Claims. (Cl. 242—147)

This invention relates to a method of controlling automatically the tension of an advancing strand, and is well adapted for broad application to control the tension of a strand of yarn, cord, rope, cable or extruded filament.

Numerous tension devices have been employed heretofore to increase the tension of an advancing strand, but the trouble with most of these devices is that they increase the tension of the strand but fail to control the tension automatically so as to impart to the advancing strand uniform tension.

When a strand is drawn forward from a supply cone or other source of supply one portion of the strand may pull off the cone or away from the supply source more readily than another portion of this strand, so that the tension of the strand as it advances along a definite path of travel may vary considerably.

It is a simple matter to place a tension device along such path of travel to increase the tension of the strand, but if the action of the tension device is to exert substantially the same retarding force on all parts of the advancing strand, it will increase the tension of the strand without imparting to the strand uniform tension.

The present method overcomes this difficulty and provides a simple and practical method for imparting a uniform tension to an advancing strand. This tension may be as low or as high as desired since a desired constant force is established, and then a balance is maintained between this force in one direction and the total tension upon the strand as it advances in the opposite direction.

Since, as above stated, the tension of a strand may vary considerably as it approaches a tension device such as herein contemplated and is to be constant upon leaving such device, then this device should operate automatically to impart to the strand a varying retarding force that will equal the difference between the tension of the strand as it arrives at this tension device and the constant tension of the strand as it leaves the tension device.

In carrying out the present method a drum or arcuate member adapted to rotate about a central axis is employed, and a weight is employed to exert a constant torque upon the drum to rotate it in one direction, while the strand to be tensioned is caused to leave the drum in the opposite direction so that its leaving tension will just equal the constant torque, irrespective of the tension of the strand as it approached this tension device.

More specifically the present method contemplates the use of a drum or other member having an arcuate surface and supported to rotate about an axis concentric to such surface. It also contemplates the use of means for exerting a constant torque upon the drum or the like to continuously urge it in one direction, so that the tendency of this drum to rotate in one direction under the constant torque will be balanced against the total retarding force exerted upon the strand at the instant it leaves the drum. This result is secured by advancing the strand toward the drum along its axis of rotation, so that the pull exerted upon the strand to advance it to this position will not produce a torque tending to turn the drum. The strand is then advanced outwardly to the periphery of the drum to be dragged over an arc of the surface of the drum, the length of which arc will vary as the drum rocks back and forth to establish a balance between the constant torque in one direction and pull upon the leaving strand in the opposite direction.

The operation is such that the constant force tending to turn the drum in one direction will be balanced by the tension of the strand as it reaches the drum plus the additional tension placed upon the strand as it drags over an arc of the drum surface. The varying tension of the strand as it reaches the drum will cause the drum to rock back and forth to decrease or increase the length of the arc over which the strand drags so that the tension of the strand as it leaves the drum will just equal the constant torque.

Various forms of apparatus can be employed to carry out the present method. One good practical form of apparatus to this end is shown in Figs. 1 and 2 of the drawing, and a modification is shown in Fig. 3.

40 In the drawing:

Fig. 1 is a side elevation of one form of tension control apparatus for carrying out the present method.

Fig. 2 is an end view of the construction of Fig. 1; and

Fig. 3 is an end view of a modification of the apparatus of Fig. 2.

In the construction shown in Figs. 1 and 2 of the drawing 10 designates a drum having the central shaft 11 which is rotatably mounted in the upper portion of the upright 12 that extends upwardly from the base plate 13. In front of the drum 10 there is disposed a thread guide comprising the upright 14 having the pig-tail 15 formed at the upper end thereof and disposed so

that the thread passing therethrough will travel along the axis about which the drum 10 rotates.

The tension device illustrated in the drawing may be employed to control automatically the tension of various types and sizes of strands from practically any source of supply. In the construction shown the tension device is employed to control the tension of a relatively heavy yarn 16 as it is drawn forward from the supply cone 17 that is rotatably supported by 18.

As this strand 16 is drawn forward from the supply package 17, it passes through the pigtail guide 15 and then outwardly through a hole 19 formed in the annular wall of the drum 10, to drag around upon a portion of the outer periphery of the drum to thereby exert a retarding force upon this strand. The strand 16 upon leaving the drum 10 may pass to any form of takeup means such for example as the takeup spool 20 which is rotatably supported at 21 and is driven in the direction indicated by the arrow by the belt 23 passing around the pulley 22.

It will be seen from the construction so far described by reference numerals that as the strand 16 is pulled forward by the rotation of the takeup spool 20, it will exert a turning force upon drum 10 tending to rotate the same in a clockwise direction viewing Fig. 2. The rotation of the drum 10 in this direction is yieldingly opposed, by a constant torque which tends to rotate the drum in the opposite direction. This torque can be supplied by a suspended weight, or a torque which will be approximately constant can be supplied by a relatively long coiled spring. In the construction shown the desired torque is supplied by the cord 24 one end of which is secured to the drum 10 at 25. This cord which is wound one or more times around the drum 10 as shown in Figs. 1 and 2 has a downwardly extending end to which the weight W is attached. This weight preferably has the auxiliary weights shown resting thereupon to regulate the downward pull exerted upon the drum 10 by the cord 24 to rotate the drum in an anti-clockwise direction with a constant torque.

The construction is such that during the operation of this tension device the drum 10 will rock back and forth as indicated by the arrow in Fig. 2 and thereby increase or decrease the length of the arc of the drum surface over which the strand 16 slides, to thereby vary the retarding force which is imparted to this strand as the result of its frictional engagement with the drum surface.

The purpose in supplying the strand 16 to the drum 10 by advancing it thereto in a direction along the axis of rotation of the drum or at a right angle to the plane in which the drum rotates, is so that the pull required to advance the strand to the drum will not exert a torque that will tend to turn the drum. The strand 16 after passing through the pig-tail guide 15 passes outwardly to the outer periphery of the drum to drag upon such outer periphery as above stated. As a result of this construction, the entire pulling force exerted upon the strands 16 at the point T at which it leaves the outer periphery of the drum tends to rotate the drum in a clockwise direction, and this pull is opposed and balanced by the torque in the opposite direction exerted by the weight W. As the pull required to advance the strand 16 to the pigtail 15, and which pulling force is herein indicated by T', varies the drum 10 will rotate in one direction or the other to vary the length of the arc of frictional contact of the strand with the outer periphery of the

drum, to thereby vary the frictional retarding force herein indicated by F.

If the torque exerted upon drum 10 by the weight W to turn this drum in a counterclockwise direction is indicated by W, and the tension upon the strand 16 as it leaves the drum 10 is indicated by T then

$$W = T$$

If the force required to advance the strands 16 to the pigtail 15 is indicated by T' and the retarding force which is produced by the friction between the strand 16 and the drum 10 as the strand is dragged over the outer surface of this drum is indicated by F then

$$T' + F = T$$

As T' varies due to the variation in the force required to advance the strand 16 to the drum, the drum will automatically rotate to vary the friction F to maintain the equilibrium

$$T' + F = T = W$$

This is what is desired to cause the strand 16 to leave the drum 10 under a constant tension irrespective of the variations in the tension of the yarn at T'.

In the construction shown the guide 15 has been provided directly in front of the drum and has a pig-tail construction since this provides an easy means for threading up the device, but if desired this guide 15 may be replaced by a thread guide supported by the drum to rotate therewith upon the drum axis. The drum 10 is shown as having a slot 26 leading to the strand guide 19 to thereby facilitate threading up of the tension device. The strand 16 may be looped around the drum 10 one or more times depending upon the amount of friction required, the number of such loops will be automatically determined by W and T', in order to produce the amount of friction between the drum and the strand 16 necessary to maintain equilibrium.

In the modified construction of Fig. 3 the operation is substantially the same as that shown in Figs. 1 and 2 except that the cord 24' is shown as wound upon a drum 27 of smaller diameter than that of the drum 10' about which the strand 16' is wrapped. Furthermore the drum 10' is given a squirrel-caged construction having the free running rollers 28 arranged so that the strand 16' will engage these anti-friction rollers instead of sliding upon the surface of the drum as in the case of Figs. 1 and 2. In this construction of Fig. 3 in which the yarn 16' rests upon the rollers 28, the drag which the drum places upon the yarn will depend upon the force required to turn these rollers.

It will be seen from the foregoing that by employing the present method any desired tension may be imparted to the yarn 16 as it leaves the drum 10 provided it is greater than the entering tension T'.

Having thus described my invention, what I claim and desire to protect by Letters Patent is:

1. The method of controlling the tension of an advancing strand, which consists in providing a rotating drum and exerting a constant torque that tends to rotate the drum about its central axis, supplying a strand to approach the drum along its axis of rotation and then outwardly to the periphery of the drum to drag over an arc of the drum surface so that this arc of contact will vary as the drum rotates, and pulling the strand from the drum in a direction to decrease this arc while said torque tends to increase the

arc, so that the tension of the strand as it leaves the drum will equal said constant torque.

2. The method of controlling the tension of an advancing strand, which consists in providing a rotating drum and exerting a constant torque that tends to rotate the drum about its central axis, supplying a strand to approach the drum along its axis of rotation and then outwardly to the periphery of the drum to drag over an arc of the drum surface in a direction to turn the drum against said torque, so that the tension of the strand as it leaves the drum will equal said constant torque.

3. The method of controlling the tension of an advancing strand, which consists in providing an arcuate member adapted to rotate about its central axis, exerting a constant torque that tends to rotate said member, supplying a strand to approach said member along its axis of rotation and then outwardly to the periphery of the arcuate member to drag over an arc thereof so that this arc of contact will vary as the arcuate member

rotates, and pulling the strand therefrom in a direction to decrease this arc while said torque tends to increase this arc, so that the tension of the strand as it leaves the arcuate member will equal said constant torque.

5. 4. The method of controlling the tension of an advancing strand, which consists in providing an arcuate member adapted to rotate about its central axis, exerting a constant torque that tends to rotate said member, supplying a strand to approach said member at a right angle to the plane in which the arcuate member rotates and then outwardly to the periphery of the arcuate member to drag over an arc thereof so that this arc of contact will vary as the arcuate member rotates, and pulling the strand therefrom in a direction to decrease this arc while said torque tends to increase this arc, so that the tension of the strand as it leaves the arcuate member will equal said constant torque.
